US00D790988S

(12) United States Design Patent (10) Patent No.: US D790,988 S
Vasiliadis et al. (45) Date of Patent: * Jul. 4, 2017

(54) SHAVER PACKAGING

(71) Applicant: Societe BIC, Clichy (FR)

(72) Inventors: Andreas Vasiliadis, Charandri-Athens (GR); Argyro Kallivretaki, Kolonos (GR)

(73) Assignee: Societe BIC, Clichy (FR)

() Term: 14 Years

(21) Appl. No.: 29/523,111

(22) Filed: Apr. 7, 2015

(51) LOC (10) Cl. 09-03

(52) U.S. Cl.

USPC D9/748

(57) CLAIM

The ornamental design for shaver packaging, as shown and described.

DESCRIPTION

FIG. 1 is rear view of an ornamental design for a translucent shaver packaging according to a first embodiment of the present invention;

FIG. 2 is a front view thereof;

FIG. 3 is a right side view thereof;

FIG. 4 is a left side view thereof;

FIG. 5 is a top view thereof;

FIG. 6 is a bottom view thereof; and,

FIG. 7 is a perspective view thereof.

The broken lines showing of razors in the figures illustrate environmental structure. All other broken lines illustrate portions of the shaver packaging. The broken lines form no part of the claimed design.

1 Claim, 7 Drawing Sheets
